UNITED STATES PATENT OFFICE.

FRANK L. FAATZ, OF LESTERSHIRE, NEW YORK.

DESIGN FOR A METALLIC SPRING-HOOK.

SPECIFICATION forming part of Design No. 26,680, dated February 23, 1897.

Application filed December 26, 1896. Serial No. 617,100. Term of patent 7 years.

To all whom it may concern:

Be it known that I, FRANK L. FAATZ, a citizen of the United States, residing at Lester-shire, in the county of Broome, State of New York, have invented and produced a new and original Design in Metallic Spring-Hooks, of which the following is a specification, reference being had to the accompanying drawing, in which I show an isometrical view thereof detached, this view being deemed sufficient to properly illustrate the same.

The leading feature of my design consists in an oblong piece of metal *a*, having its corners rounded, as shown at *b*, and one end 15 turned partially over, as shown at *c*, its con-

figuration and form being substantially as shown in the drawing. *d* are perforations by which it may be secured.

Having described my invention, what I claim is—

The design for a metallic spring for housings substantially as herein described and shown.

In witness whereof I have hereunto set my hand this 4th day of December, 1896.

FRANK L. FAATZ.

In presence of—

H. C. OLMSTED,
H. E. VOLK.
